(57) **CLAIM**

The ornamental design for a networking device enclosure, as shown and described herein.

DESCRIPTION

FIG. 1 is a perspective view of a networking device enclosure showing the new design;

FIG. 2 is another perspective view of the networking device enclosure of FIG. 1;

FIG. 3 is a front view of the networking device enclosure of FIG. 1;

FIG. 4 is a rear view of the networking device enclosure of FIG. 1;

FIG. 5 is a left-side view of the networking device enclosure of FIG. 1;

FIG. 6 is a right-side view of the networking device enclosure of FIG. 1;

FIG. 7 is a top view of the networking device enclosure of FIG. 1; and,

FIG. 8 is a bottom view of the networking device enclosure of FIG. 1.

The broken lines in the drawings show portions of the networking device enclosure that form no part of the claimed design.

The shading in the drawings shows contour.
